Specification for Design.

Patented July 12, 1910.

Application filed February 5, 1910. Serial No. 542,331. Term of patent 14 years.

To all whom it may concern:

Be it known that I, HERBERT M. DAWLEY, a citizen of the United States, residing at Buffalo, in the county of Erie and State of New York, have invented a new, original, and ornamental Design for Vehicle-Lamps, of which the following is a specification.

The accompanying drawing represents in Figure 1 a front elevation and in Fig. 2 a plan of a lamp embodying the design.

The main feature of the design is the substantially vasiform or downwardly tapering

body of polygonal shape in cross-section having tapering and curved glass sides and surmounted by a top provided with an ornamental knob.

I claim:

The ornamental design for a vehicle lamp, as shown and described.
